United States Patent Office.

ALONZO C. ARNOLD AND EBENEZER BLACKMAN, OF NORWALK, CONNECTICUT.

Letters Patent No. 74,271, dated February 11, 1868.

IMPROVEMENT IN LAMPS.

The Schedule referred to in these Letters Patent and making part of the same.

TO ALL WHOM IT MAY CONCERN:

Be it known that we, ALONZO C. ARNOLD and EBENEZER BLACKMAN, both of the town of Norwalk, county of Fairfield, and State of Connecticut, have invented a new and useful Improvement in the Mode of Constructing Lamp-Glasses and Arrangements for Attaching the same to Lamps; and we do hereby declare that the following is a full and correct description thereof, reference being had to the accompanying drawing and to the letters of reference marked thereon.

The nature of our invention consists in an improved shape of the glass chimney, and the arrangement for attaching the same to the lamp.

To enable others skilled in the art to make and use our invention, we will proceed to describe the same.

The Drawing.

Figure 1 is a view of a lamp with the glass chimney placed on the same, and the arrangements for attaching the top, springs, &c.

A is a section of the glass chimney, which we make to rise up vertically from the bottom or base part, about three-fourths of an inch, and then form an indentation, C, or neck to receive the end of the four vertical springs D, which are made with a curved catch, at the upper end E, to correspond and pass into the indentation C to hold on the glass chimney A, and the tension of the springs and catch E is regulated to the necessary strength required to prevent the chimney from toppling over when the lamp is held in an extremely inclined position; also, so regulated that the chimney can be easily removed and replaced. From and above the neck C the glass takes a globular shape and tapers to the top, the same as usual. The metallic device F, to support the chimney, we make with the usual screw for attaching, and the mode of raising and lowering the wick is the same as other lamps. The part to receive the glass and cone we make flat at G, but sunk down within the circumference of the cone B, for the ventilating-perforations. The springs D are attached to the outer edge of the flat part G, rising up perpendicularly from the same. The perforations are all within the circle of the cone B, so that the air for combustion passes within the same, directly to the base of the flame, and by that means is more fully consumed, and makes it less liable to smoke, and by the air passing within the cone it keeps it cool, and also the base of the glass is but slightly affected by the heat of the flame.

The utility of our improvement is in the facility of removing and replacing the chimney, and the light is thrown downwards without obstruction; also, the cone and base of the glass remaining all the time comparatively cool.

What we claim as our invention, and desire to secure by Letters Patent, is—

The glass chimney A, formed as herein described, in combination with the arrangements of the vertical springs D, flat perforated base G, and cone B, in the manner substantially as and for the purpose herein set forth

ALONZO C. ARNOLD,
EBENEZER BLACKMAN.

WITNESSES:
